UNIVERSAL SEWING KIT

James H. Reichart, Muncie, Ind.

Application August 20, 1938, Serial No. 225,893

9 Claims. (Cl. 223—107)

This invention relates to a sewing box. The chief object of this invention is to provide a sewing box which not only is of ornamental character but which is primarily of utilitarian character and characterized by a container portion adapted to receive sewing accessories, such as scissors, tape measure, and the like, and associating therewith a spool tray suitably supporting a plurality of spools, the tray being hollow at its central portion to permit access to the major portion of the container when the tray is supported thereby, and a cover construction which normally conceals the interior of the spool tray and the container.

A further object of the invention is to construct the container portion, cover and tray so that omission of the tray does not destroy the utility of the container portion and cover as a covered receptacle.

Another object of the invention is to provide on the interior of the cover a cushion for pins, needles and the like.

Another object of the invention is to provide on the interior of the cover a thimble support.

Another object of the invention is to provide, when desired, on the exterior of the cover a pocket arrangement adapted to support a spool, if desired, pins, buttons, fasteners and the like.

Another object of the invention is to provide, when desired, a thread cutter arrangement.

The chief feature of the invention consists in the provision of means whereby all of the aforesaid objects are accomplished.

Other features of the invention will appear more fully hereinafter.

The full nature of the invention will be understood from the accompanying drawings and the following description and claims:

In the drawings,

Fig. 1 is a central sectional view through one form of the invention, parts being shown in the closed position.

Fig. 2 is a top plan view of half of one form of the invention, the cover being removed.

Fig. 3 is a top plan view of half of one form of the invention including a pocketed type cover.

Fig. 4 is a sectional view taken on line 4—4 of Fig. 3 and in the direction of the arrows.

Fig. 5 is a sectional view of the portions of the adjacent cooperating parts at their association.

Fig. 6 is a similar view of still a further modified form of the invention.

Fig. 7 is a top plan view of a portion of one form of container portion and associated tray

(spindle spool type) with cover removed, and provided with thread cutting means.

Fig. 8 is a similar view of a similarly provided structure, the tray being of the spindleless type.

Fig. 9 is a vertical sectional view of the side portion of the container portion and cover (shown in full lines) and in the relative positions when a tray (shown in dotted lines) is associated therewith.

Fig. 10 is a horizontal sectional view of a portion of a tray provided with a thread cutter.

Fig. 11 is a sectional view of a modified form of pin cushion and thimble holder.

In the drawings 10 indicates a bowl like container having a relieved bottom portion 11, and an inwardly directed upper side wall 12 provided with a relatively wide opening 13. Portions 10 and 12 are suitably secured together as indicated at 14, or the portions may be secured together by any other convenient connection if made in two pieces or may be formed from a single piece of sheet metal or of plastic composition or the like.

Suspended from the edge 13 and nested in the container is a spool tray having the trough like portion 15, the inner peripheral edge 16 of which is of beaded character and which provides a relatively large central opening so that access may be had through the tray into the portion of the container therebeneath for the removal and insertion of scissors, tape measure and the like, constituting the usual sewing accessories.

The upper edge—see Fig. 1—of the spool tray is extended outwardly as at 17 and thence upwardly as at 18 and thence outwardly and downwardly as at 19. The portions 18 and 19 form the support for the spool tray upon the edge 13 of the container. Thus, the spool tray is suspended in the container in nested relation.

The portions 18 and 17 form a seat for the in-turned edge 20 of a relatively flat dished cover 21 centrally apertured as at 22. Adjacent the aperture 22 the cover is progressively offset as at 23a, 23b and 23c. This forms an ornamental cover. A bolt or like anchorage 24, extends through the opening 22 and mounts a knob 25 thereon by which the cover may be removed, exposing the spool tray and the container interior through the opening in the spool tray.

As shown clearly in Fig. 2, the spools A may lie in the trough like arrangement in end to end relation. Also as shown in Fig. 2, the spools in certain instances, may be positioned in upright relation, these spools being indicated by the letter B and they are retained in that po-

sition by the spindles 26 having an enlarged portion 27 bearing on the interior of the trough like spool tray and having the portion 28 extending through the same and enlarged as at 29 for rigidly mounting the spindle on the tray. The upper end of the spindle 26 terminates below the portion 17. The bottom portion of the spool tray is of relatively shallow curve character, as illustrated, so that the vertical spools have diametrical engagement with the trough portion, as shown in Fig. 1, and the lower end of the spool just clears the enlargement 27 of the spindle 26.

The advantage of the spindle type spool support is that the thread on the spool is kept out of contact with the surface of the tray and also all of the thread surface of the spool is subjected to about the same amount of light, so there is uniform fading should the same occur. This type of support also has an additional advantage, to-wit, that the seamstress need only engage the loose end of the thread and pull the thread, and the thread will unwind by spool rotation on the spindle. The vertical type spool support makes it easy to see the size, kind and color of thread on the spool.

The disadvantage of this type of mounting is that if the loose end of the thread on the spool is not secured to the spool, the loose end loops may fall down along and around the spool and the spindle.

The advantage of the end-to-end arrangement of the spools is that the thread may be unwound therefrom by merely pulling the same. When the required amount of thread is removed, the spool may be reversely rotated with the finger and the loose thread end rerolled on the spool and when so wound, there is no displacement or tangling of the loose end loops. Because the spools lie in a circular tray, the ends of adjacent spools are arranged in an angular position, thereby exposing the sizes stamped on the spool ends.

The disadvantage of this type of mounting is that the thread surface which is uppermost, is exposed to the light while the thread surface which is positioned immediately adjacent the trough like portion of the tray is subjected to less light and, therefore, this arrangement permits possibility of unequal fading if the spools remain uncovered and exposed to sunlight for any appreciable time. For the same capacity tray, more spools may be accommodated in a tray having spindles than in a tray provided with no spindles.

One advantage of end to end positioning is that the full color value of the thread on the several spools is exposed for ready selection, whereas the spindle type spool mounting does not so expose the colors so easily.

It is evident that it is easier to remove from and replace in the tray a spool when the tray has no spindles than it is to remove a spool from a spindle and then replace the spool on the spindle, since definite location is required for the latter should removal and replacement of the spool be necessary or desirable.

Each of these types of spool support, therefore, has certain advantages and certain disadvantages. There is, however, disclosed in Fig. 2 a tray which combines both types of spool supports and it is to be understood that either type of support may be provided without provision of the other type or that both may be utilized as shown.

Reference will now be had to Fig. 1. In said figure, there is disclosed in the offset or socketed portion of the cover 21 a spacing washer 30 through which the bolt 24 extends. Bearing on the washer is a dished disc 31 and similarly apertured. It is of slightly less diameter than the diameter of the offset portion 23a, as shown, or it may be of the same or slightly greater diameter, if desired.

Included between the offset portion of the cover and the disc 31 is a cushion 32 which may be of felt, or the like. It may also be provided with lubricant. It may also be impregnated with sharpening material, such as emery dust and the like. The peripheral edge as indicated at 32a, of this cushion disc, is exposed between the disc 31 and the portion of the cover immediately adjacent the offset portion 23a thereof.

As shown clearly in Fig. 1, the cushion is of partial spherical form or of relatively flat conical type, the purpose of which is clearly illustrated by referring to the pin C and the needle D shown. The pin C, when projected into the cushion, has its head portion positioned at a considerable distance from the interior of the cover 21 so it may be readily grasped for removal. In a similar manner the needle has its exposed end portion positioned at a considerable distance from the interior of the cover.

The disc 31 may be of resilient character and may be brought into engagement in its limiting position against the fibre washer which in turn bears upon the interior of the cover adjacent the opening 22 therein. Another spacer 33 is provided which bears on the inner face of the disc 31 at one end and at its opposite end there is mounted a flexible rubber like disc 34 that projects beyond the peripheral outline of the spacer 33. A washer 35 bears against the opposite face of the rubber like disc 34 and against said washer bears the head portion of the bolt 24, before mentioned.

The diameter of the rubber like disc 34 is the same or slightly greater than the diameter of a thimble at its mouth or entrance so that the thimble, indicated by the letter E in Fig. 1, may be slipped over said rubber like disc 34 and the spacer 33 until its open end engages the metal disc 31 when, due to the taper in the thimble the rubber like disc frictionally retains the thimble on the cover. This disc will retain substantially any size thimble.

As shown clearly by a comparison of the positions indicated by needle D and pin C, the pins and needles are held in concave or conical like position in rayed relation, thereby making it impossible for one pin or needle to hide the adjacent needle and pin, and as shown, there is a considerable angle of accommodation provided by the aforesaid pin cushion construction.

The lubricant and sharpening materials serve to maintain the pins and needles in sharp and rustproof condition.

It will also be apparent if a plurality of needles of different sizes are secured in the cushion that the cover may be held by the knob 25 in one hand and there is immediately exposed the various needles so that the seamstress may make the desired selection therefrom without the necessity of handling a large number of needle packages in order to obtain the desired size of needle, or of trying to make a selection from a forest of needles and pins in the usual pin cushion.

The inturned edge of the cover 20 to a certain

extent eliminates the bell sound effect in the cover.

In Figs 3 and 4 a modified form of cover construction is illustrated and numerals of the one hundred series indicate like or similar parts. 120 indicates the peripheral edge of the cover and 121 the dished body portion thereof. This embodiment of the invention, however, illustrates the cover adjacent its outer edge as being provided exteriorly with a plurality of spaced 10 pockets 140 which near their inner portions have a relatively circular outline flat portion 141 therein. The pocket walls merge as at 142, 143 and 144 into the remainder of the cover. These pockets serve as separate trays for buttons, 15 fasteners and pins, the pins being obtained from the paper roll normally contained within the container.

In Fig. 5 a modified form of the invention is illustrated and herein numerals of the two hundred series indicate like or similar parts. This form of the invention differs from that shown in Fig. 1 in that the portion 219 extends upwardly instead of downwardly to overlie the cover portion 212. Also in this form of the invention, the cover may be provided with a depending flange 220a. This type of construction permits the trough to be removed and the cover to be mounted directly on the container at the edge 213 thereof should such an arrangement be desired.

Fig. 6 illustrates a further modified form of the invention and numerals of the three hundred series indicate like or similar parts. In this form of the invention the same function is accomplished by the turned back depending portion 320a of the cover 321. In this form of the invention, the flange 319 on the tray extends downwardly instead of upwardly, as shown in Fig. 5. This form of the invention also is capable of arrangement such that the cover may be mounted on the container without the tray being interposed therebetween. Of course, it is to be understood the trays shown in Figs. 5 and 6 may be of spindle or spindleless character, as illustrated in Figs. 1 and 2, and previously described or be of both characters.

It will be obvious from an examination of Fig. 1 with relation to spools A that if, as and when desired, the cover 21 may be inverted from the position shown in Fig. 1 and the knob 25 will readily seat in the wide mouth or opening 16 of the spool tray without interference therefrom and the curled edge 20 of the cover can again be seated on the ledge 17 of the spool tray.

Of course, it is to be understood when the invention includes the pins 26, these must of necessity be of such a height that they do not engage the cover when in inverted relation in and supported upon said tray. This inversion feature may be utilized by the seamstress whenever desired, in the continued use of the device. However, it has a separate advantage, to-wit, it permits the inverted nesting of the cover with respect to the spool tray so that the tray, cover and container may be assembled in nested relation in a minimum volume, without any projection interfering with small packaging.

It will also be noted in Fig. 1 that the thimble E when utilized, does not project beyond the plane of the beaded edge 20 so that if a thimble be packaged with the container, the thimble will not constitute an obstruction to minimum volume packaging. Similarly, the spools A may be

packaged therein without interference with the cover in its inverted relation for packaging or use. In the latter instance, due to the dimension of the parts illustrated, the cover retains the spools A in the trough even though the carton containing the device be inverted, which would not be the case if the cover were mounted as shown in Fig. 1 and the device packaged with the parts in that position.

It also will be clear from an inspection of Fig. 1 that when the seamstress removes the cover from the device and sets the same on a support such as a table or the like, the thimble will not constitute a bearing for the cover but the thimble just clears said support, the cover being supported on its edge 20. The dome shape of the cover, therefore, not only is provided so as to insure clearance of pins, needles and the like, mounted in the cushion but is also of such character that it serves as a spool retainer during shipment when the cover is inverted, because the dome shaped portion of the cover then is in depressed relation with respect to the spool tray.

Furthermore, it is to be understood the spool tray, as shown in Figs. 1, 2 and 5, may have formed therein adjacent the spindles or even if the spindles were not provided in similarly spaced relation, flat portions of the character, shown at 141 in Fig. 3. This would require the bottom to be extended in flattened relation and the side walls remote from the portions 17 and 16 and adjacent the bottom 15 to be correspondingly formed so as to merge into each of said flattened portions. When thus formed, there would be provided a flat bottom space for the several spools permitting the same to be positioned in the spool tray in vertical relation.

In Fig. 7 of the drawings, numerals of the four hundred series indicate like or similar parts, although herein the spools of thread are again designated by the letter B. Herein the side wall portion of the tray near the top—in other words adjacent the offset portion 417—is provided with a plurality of inwardly struck portions 400. These portions are formed by aperturing the side wall as at 401—see Fig. 10. The arrangement is such that between each pair of spools there is provided one projection. The method of utilizing the same is set forth hereinafter with reference to Fig. 8. Each projection constitutes a thread cutter.

In Fig. 8 numerals of the five hundred series indicate like or similar parts. The form of the invention herein is such that the spools designated by the letter A may be moved around in the trough 515 of the tray until the selected spool of thread A is positioned adjacent the thread cutter 500 formed in the manner shown in Fig. 10 for thread cutter 400.

The loose end of the thread A' is then passed through the opening formed by the thread cutter and the finger of the seamstress indicated by the letter C, presses the thread against the side wall of the tray immediately adjacent the thread cutter. The other hand of the seamstress then pulls on the loose end of the thread A', after the desired amount of the thread previously has been unwound from the spool, and since the thread is held by the finger C, the thread is severed by the cutter 500. The severance is of the following character. It is somewhat frayed. The advantage thereof is as follows:

This fraying permits the thread to be readily threaded through the eye of the needle. The

employment of the thread cutter prevents cutting of the fingers of the seamstress by severing the thread by hand. Cutting of the thread by a shears or razor blade provides an end that is blunt and the severance is such that when the thread is just slightly less than the size of the eye of the needle, the severance will spread slightly the fibers of the thread so that it is difficult to thread the needle. The present severance arrangement, therefore, provides sufficient fraying as distinguished from spreading so that the long frayed ends of the fibres serve as a pilot, as it were, to facilitate threading of a needle the eye of which is but slightly greater than the diameter of the thread utilized.

The advantages of the thread cutter illustrated in Figs. 7 and 8, Fig. 7 representing the spindle type tray and Fig. 8 the spindless type tray embodiments of the invention, is that the thread cutter arrangement is always available in juxtaposition to the thread supply. Therefore, it cannot become lost or mislaid like scissors or a razor blade.

In Fig. 9 of the drawings, there is illustrated an embodiment of the invention previously broadly described. Herein numerals of the six hundred series indicate like or similar parts. 610 represents the bottom of the receptacle, 612 the top portion thereof, 614 the union therebetween, if, as and when the receptacle is so formed. Herein the upper edge 613 of the receptacle is provided with a downwardly directed flange portion 603 which in turn is provided with an inwardly directed flange portion 604, in turn provided with a protected edge in the form of a return bend arrangement or beading 605. The diameter of the opening defined by the beading is slightly greater than the diameter of the tray herein shown dotted and indicated by the numeral 615. The tray has a beaded central opening 616 as shown and includes at its upper edge an outwardly directed flange portion 617, an upwardly directed extension 618 thereof, and then an outwardly and downwardly directed portion 619 which overlies the upper portion 612 adjacent the upper edge 613 thereof, all as shown in Fig. 9. Whenever desired, portions 618 and 619 may be omitted.

The cover 621 has the beaded edge 620 and said beaded edge is adapted to rest in the grooved channel or seat provided by the portions 618 and 617 of the tray or the portions 603 and 604 at the upper edge of the receptacle or container forming portion of the device. If the tray is not utilized, the cover is in direct contact with the base portion of the device. If the tray is utilized, the cover is positioned as shown in Fig. 9 with reference to the tray and the base or container portion.

In Fig. 11 a modified form of pin cushion and thimble holder is illustrated. Numerals of the 700 series similar to the primary numerals indicate like or equivalent parts. 721 indicates a bowl type cover or bowl like portion thereof, 725 the handle or knob in ball form apertured at 725a to receive a screw 724, the head of which bears upon washer 735 which bears upon the rubber disc 734 in turn bearing on the spacing sleeve (of wood) 733 bearing upon disc 731 in turn bearing upon the felt disc or pin cushion member 732.

In this form of the invention, the spacing sleeve 30, see Fig. 1, is omitted. In this form the radius of curvature, as it were, of cover 721 is such that it cannot cooperate with cushion

732 and disc 731 so instead of the cooperating cover portions 23a, 23b and 23c—see Fig. 1—there is provided another disc 723 similar to disc 731 and serving the same function as portions 23a, 23b and 23c. The screw 724 extends through members 735, 734, 733, 731, 732, 723 and 721 and into handle 725.

While the invention has been described in great detail in the foregoing specification and similarly illustrated in the drawings, the same is to be considered illustrative and not restrictive in character. The various modifications herein disclosed, as well as others which will readily suggest themselves to persons skilled in this art, are all considered to be within the broad scope of the invention, reference being had to the appended claims.

The invention claimed is:

1. In a sewing box, the combination of an open mouth sewing accessory container, a hollow tray seatable therein and supported solely at its outer edge by the mouth edge, and a cover therefor supported solely at its edge by the outer edge of the tray, the tray being of depressed character and nestable in the container.

2. A device as defined by claim 1, characterized by the cover including a plurality of spaced, peripherally arranged pockets upon the cover exterior adjacent the periphery thereof.

3. A sewing box cover including an outwardly directed centrally offset portion, a knob exteriorly thereof, means extending through the cover and anchoring the knob, and pin cushion means mounted in the offset portion interiorly of the cover and by said anchoring means including a cushion disc for receiving pins and the like, a dished disc bearing thereon and operatively clamping the cushion disc between the dished disc and offset portion whereby peripherally received pins have their exposed portions extending outwardly from the adjacent portion of the cover.

4. A device as defined by claim 3, characterized by the addition of a non-metallic spacing washer between the cover and dished disc and surrounded by the cushion disc, and serving as a stop to prevent needle and pin point engagement with the anchoring means.

5. In combination a main support having an offset therein, a cushion nested therein, an elongated retainer means securing the cushion to the support and exposing the peripheral edge of the cushion, a sleeve on said means and bearing on the cushion, and a rubber-like disc spaced by said sleeve from said cushion and of a diameter slightly greater than that of the sleeve, said disc, sleeve and cushion being secured by the elongated retainer means to the support.

6. A device as defined by claim 1, characterized by the cover having a dished portion and by the addition of a central handle and a thimble support, the latter depending from the interior of the cover within the dished portion whereby when the cover is inverted for shipping purpose, the thimble support does not project beyond the plane including the peripheral edge of the cover and the handle registers with the tray aperture.

7. A device as defined by claim 1, characterized by the cover including an upwardly directed dished portion, an upwardly directed handle thereon, and by the addition of elongated means juxtaposed relative thereto and upon the cover interior within the dishing thereof and anchoring the handle, whereby when the cover is inverted upon the container, the handle is

nested within tray hollow portion and no part of the elongated means projects above the plane of the inverted cover, said cover including a plurality of spaced peripherally arranged pockets upon the cover exterior adjacent the periphery thereof, the inner edge of the hollow tray being below the outer and supporting edge thereof whereby when the cover is inverted the peripheral portions between the pockets thereof clear the tray inner edge.

8. A device as defined by claim 1 characterized by the cover including an upwardly directed dished portion, an upwardly directed handle thereon, and sewing utensil means juxtaposed relative thereto and upon the cover interior within the dishing thereof, whereby when inverted upon the container, the handle is nested

within the tray hollow portion and no part of the sewing utensil means projects above the plane of the inverted cover.

9. A cover device as defined by claim 3 characterized by the knob anchoring means projecting inwardly from the cover an appreciable distance, an elongated rigid sleeve bearing upon the dished disc and enveloping said means, a rubber-like disc bearing on the sleeve and enveloping said means and of a diameter greater than that of the sleeve and slightly greater than that of a thimble for frictional mounting of a thimble upon the cover, said anchoring means at its inner end bearing upon the rubber-like disc for knob mounting and assembly retention upon and within the cover.

JAMES H. REICHART.
